Primary Examiner — Kevin Rudzinski*Assistant Examiner* — John Reickel(74) Attorney, Agent, or Firm — Sterne, Kessler, Goldstein & Fox P.L.L.C.(57) CLAIM

The ornamental design for a display screen or portion thereof with graphical user interface, as shown and described.

DESCRIPTION

FIG. 1 is a front view of a display screen or portion thereof with graphical user interface showing our new design; FIG. 2 is a front view of another embodiment thereof; FIG. 3 is a front view of another embodiment thereof; and, FIG. 4 is a front view of another embodiment thereof. The broken lines in the figures show a display screen or portion thereof, and form no part of the claimed design.
